UNITED STATES PATENT OFFICE.

WILLIAM D. GRAY, OF MILWAUKEE, WISCONSIN, ASSIGNOR TO THE EDWARD P. ALLIS & COMPANY, OF WISCONSIN.

FRICITION-CLUTCH.

SPECIFICATION forming part of Letters Patent No. 408,012, dated July 30, 1889.

Application filed April 22, 1889. Serial No. 308,179. (No model.)

To all whom it may concern:

Be it known that I, WILLIAM D. GRAY, of Milwaukee, in the county of Milwaukee and State of Wisconsin, have invented certain 5 Improvements in Friction-Clutches, &c., of which the following is a specification.

The aim of my present invention is to provide a simple, durable, and efficient clutch, for connecting shafts and the like, which will 10 readily and quickly respond to the action of its operating mechanism.

To this end the invention consists, essentially, of a coiled spring having one end connected to one of the shafts to be coupled and 15 its other end free to move, said spring arranged to be expanded to frictionally engage a shell or its equivalent, keyed or otherwise firmly secured to the opposing shaft, and of means for expanding the spring.

20 In the accompanying drawings, Figure 1 is a side elevation of my improved clutch partly in section. Fig. 2 is a vertical section of the same on the line $x-x$ of the preceding figure. Fig. 3 is a top plan view of the wedge and adjacent parts of the spring, portions of the shell being broken away. Fig. 4 is an end elevation of the spring and the shell, looking in the direction of the arrow, portions of the operating mechanism being removed.

25 Referring to the drawings, A and B represent the shafts which it is desired to couple together. These shafts are arranged in line end to end, and are provided, respectively, with the shell or cup C and the coiled spring D. The end of the shaft B is seated in the shell to revolve freely. The spring D is formed, 30 preferably, of cast-iron, and consists of the series of coils diminishing, as usual, in size as the center is approached, where it terminates

35 in a tubular head or collar d, through which the shaft B passes and to which it is keyed at d' . The outer end of this spring is free to move to a limited extent, the purpose of which will hereinafter appear. The shell C, 40 fixed to the shaft A, is formed with the overhanging flange c, within which the spring is arranged in such manner that as the latter is expanded its outer coil will frictionally engage the inner face of the flange c. The outer 45 coil of the spring is provided at a point opposite to and at a short distance from its free

end with a shoulder e, formed, as shown in Fig. 2, by the sudden outward deviation from the spiral course of the inner coil. From this point the outer coil extends in a circular path 55 within the shell C. The spring is expanded by means of a wedge e' , arranged to be moved axially between the free end of the spring and the shoulder e. This wedge is operated in a manner similar to that represented in an 60 application filed by me on the 11th day of March, 1889, Serial No. 302,879, being adjustably mounted on an upwardly-extending arm f of the forked lever f' . The lever has one of its ends pivoted between ears $f^2 f^3$, formed 65 on the tubular head d of the spring, and has its other end pivotally connected to a sliding collar f^4 on the shaft B by means of a link f^5 . This collar is grooved circumferentially to receive the encircling ring f^6 , which is connected 70 by links f^7 to a hand-lever f^8 , supported in any suitable manner.

From the foregoing description it will be seen that as the wedge is moved axially inward between the free end of the spring and 75 the shoulder e it will act to force the end of the spring outward, which motion will be transmitted through the elastic coils and will cause the outer coil of the spring to engage the inner peripheral face of the flange at all 80 points, thereby securing the shaft carrying the spring fast to the shaft carrying the shell.

It will be observed that owing to its extreme elasticity the spring will readily resume its normal position out of contact with the 85 shell as the wedge is withdrawn, and will quickly respond to the expansive force of the wedge as it is inserted, thus insuring an effective and simple clutch.

In order that the friction between the clutch 90 and shell may be such as to cause the one to readily partake of the motion of the other and to prevent slipping, I attach to the peripheral surface of the outer coil a covering g, composed of leather, fiber, wood, or other suitable 95 material.

In order that the free end of the wedge may be supported as it is moved inward to expand the spring, I commonly provide the spring with the plate e^2 , located, as shown in Fig. 2, 100 at the side of the shoulder e. This plate also serves as a guide for the free end of the spring.

Having thus described my invention, what I claim is—

1. In a friction-clutch, the external shell having the overhanging flange, the central shaft revoluble independently of the shell, the intermediate driving-spring fixed to the shaft and coiled in a plane at right angles to the axis, and an expanding device, substantially as shown, mounted between the outer 10 convolutions of the spring, whereby the spring may be positively enlarged to frictionally engage the shell.

2. The external flanged shell and the central shaft revoluble independently of said 15 shell, in combination with the intermediate driving-spring fixed at its inner end to the shaft and provided at the outside with the

shoulder opposing its end, and the wedge acting between said shoulder and end.

3. In a friction-clutch, the combination of 20 the shell C, the coiled expansible driving-spring with its central shaft-receiving hub d and ears f³ thereon, the lever pivoted to said ears, and the wedge connected to the lever and acting within the spring to expand the 25 same.

In testimony whereof I hereunto set my hand, this 30th day of March, 1889, in the presence of two attesting witnesses.

WILLIAM D. GRAY.
